UNITED STATES PATENT OFFICE.

WILLIAM MILT. BROWN, OF JOHNSTOWN, PENNSYLVANIA, ASSIGNOR TO
THE LORAIN STEEL COMPANY, OF OHIO.

DESIGN FOR A CONTACT-BOX COVER.

SPECIFICATION forming part of Design No. 29,795, dated December 13, 1898.

Application filed November 16, 1898. Serial No. 696,649. Term of patent 14 years.

To all whom it may concern:

Be it known that I, WILLIAM MILTON BROWN, of Johnstown, in the county of Cambria and State of Pennsylvania, have invented a new and original Design for Contact-Box Covers, of which the following is a specification, reference being had to the accompanying drawings, which form a part thereof.

Figure 1 of said drawings is a perspective view of my contact-box cover, and Fig. 2 is an inverted perspective view of the same.

The leading feature of the design is a contact-box cover having the design shown in the drawings.

The cover is of rectangular shape and has its top crowned, as shown. It is formed with corrugations A on its top side, with bolt-holes B B' passing through it, and with the cup-

receiving opening C and the lugs D on its under side.

The conformation of parts shown enables me to provide a contact-box cover of a pleasing appearance and at the same time well fitted for the uses to which those articles are subjected.

Having thus described my invention, what I claim as new, and desire to secure by Letters Patent, is—

The design for a contact-box cover substantially as shown and described.

In testimony whereof I have affixed my signature in presence of two witnesses.

W. MILT. BROWN.

Witnesses:

RICHARD EYRE,
H. W. SMITH.
